UNITED STATES PATENT OFFICE.

FRANCIS A. JIMERSON, OF ATHENS, PENNSYLVANIA, ASSIGNEE TO INGERSOLL-RAND COMPANY, OF JERSEY CITY, NEW JERSEY, A CORPORATION OF NEW JERSEY.

HANDLE AND INLET-CONTROLLING-VALVE CONSTRUCTION FOR PNEUMATIC TOOLS.

1,160,617.

Specification of Letters Patent. Patented Nov. 16, 1915.

Application filed March 20, 1915. Serial No. 15,861.

To all whom it may concern:

Be it known that I, FRANCIS A. JIMERSON, a citizen of the United States, residing at Athens, in the county of Bradford and State of Pennsylvania, have invented a certain new and useful Improvement in Handle and Inlet-Controlling-Valve Construction for Pneumatic Tools, of which the following is a specification.

10 This invention relates to the handle construction of pneumatic tools, and more particularly to tools having a handle which operates a valve for the purpose of controlling the admission of fluid to the cylinder.

15 The object of this invention is to provide a simple and durable handle construction for tools of this type. With this object in view a handle and valve construction has been devised, a practical embodiment of which is 20 represented in the accompanying drawings, in which—

Figure 1 shows a longitudinal section through the rearward part of such a tool with the handle and valve in operating position, Fig. 2 shows a similar section taken at right angles to the section shown in Fig. 1, showing the handle and valve in non-operating position, Fig. 3 shows a side elevation of the rearward part of the tool, Fig. 4 shows a transverse section on the line 4—4 of Fig. 1, and Fig. 5 shows a rear end elevation of the tool.

In the drawings is shown only the rear end of the pneumatic tool, the cylinder and piston construction being of any desired type, such as for instance is shown in the patent to Clement, #928,181, dated July 13th, 1909. The tool as shown comprises a cylinder 1, at the rear end of which is a back head 2, also of cylindrical contour. Seating in a slot in the rear face of the back head 2 is a transverse yoke bar 3, the ends of which project transversely beyond the back head 2. To secure the cylinder 1, back head 2 and yoke bar 3 in rigid relation to each other bolts 4 are provided, which pass through lugs 5 on the rear end of the cylinder and through the projecting ends of the yoke bar 3, these bolts 4 fitting in longitudinal depressions in the sides of the back head 2. Nuts 6 are provided on the rear ends of bolt 4 by means of which the cylinder 1, back head 2 and yoke bar 3 can be tightly secured together. Slidably mounted on the back head 2 is a handle 7 which comprises

a rearward gripping portion 8 and a sleeve portion 9, which fits the outer surface of the back head 2 and can move longitudinally thereon. In opposite sides of the rear portion of sleeve 9 are slots 10 into which project the ends of the yoke bar 3, the contact of the side faces of these slots with the edges of the yoke bar 3 serving to partly guide the movement of the handle on the back head 2 in a straight line, while the contact of the forward faces of these slots with the forward faces of the ends of the yoke bar 3 limits the rearward movement of the handle. The sleeve portion of the handle is also guided longitudinally on the back head 2 by longitudinal depressions which fit the outer surfaces of bolts 4. Through another slot 11 in the sleeve 9 passes the inlet hose connecting nipple 12 of the tool, this nipple being threaded into the side of the back head 2. From the inner end of the hose nipple 12 a passage 13 leads to a port 14 in the side of a valve sleeve 15 set centrally in the back head 2, while from the side of the valve sleeve 15 directly opposite the port 13 a port 16 connects with a passage 17 which supplies fluid to the cylinder 1 for the operation of the tool. Sliding in the valve sleeve 15 is a controlling valve 18. This valve 18 is cylindrical in shape and is provided with a depression 19 which when the handle and valve are in the position shown in Fig. 1 permits the passage of fluid from the inlet nipple 12 to the passage 17, so that the tool can operate, while when the handle and valve are in position as shown in Fig. 2 no fluid can pass to the passage 17 and the action of the tool is stopped. The forward end of the valve sleeve 15 is closed and to the inside of this portion of the valve sleeve a small air port 20 leads from the inlet nipple 12 which admits pressure constantly against the forward end of valve 18, maintaining the back end of valve 18 always in contact with handle 7 and keeping valve and handle in closed position shown in Fig. 2, except when pressure is applied by the operator's hand to the handle grip 8. A buffer 21, of leather or other suitable material, is provided on the upper end of the back head 2 to cushion the contact between the handle and the back head.

The operation of this handle construction and valve will be easily understood from the above description. When pressure from

the operator's hand is not exerted on the handle, fluid pressure acting through port 20 against the forward surface of the valve 18 will force the valve to a closed position, 5 lifting the handle with it to the position shown in Fig. 2, thus automatically shutting off the flow of fluid from passage 17 and stopping the operation of the tool except when the handle is purposely pressed forward. When it is desired to put the tool in 10 operation, the handle and consequently the valve 18 are pushed down to their foremost position, allowing air to pass by the depressed portion of the valve 18 and into the passage 17. When the tool is not in use the 15 pressure of air acting through port 20 will maintain the valve 18 and the handle in closed position until the flow of air from the supply is closed off.

20 It is to be understood that while the present showing and description discloses only one specified modification of the invention, other forms and modifications are included in the spirit and scope of the same, as expressed in the appended claims.

What I claim is:

1. In a handle construction for pneumatic tools, a cylinder, a back head, bolts securing said back head to said cylinder, a handle 30 comprising a sleeve portion slidably mounted on the outside of said back head, means for limiting the movement of said handle on said back head, and a valve for controlling the flow of fluid to said cylinder moving with said handle.
2. In a handle construction for pneumatic tools, a cylinder, a cylindrical back head on the rear end of said cylinder, a yoke bar across the rear end of said back head, bolts 40 passing through the ends of said yoke bar and securing said cylinder back head and yoke bar together, a handle having a sleeve portion slidably mounted on said back head, said sleeve portion having guiding slots into 45 which the ends of said yoke bar project, a

passage in said back head for admitting fluid to said cylinder and a valve for controlling said passage moving with said handle.

3. In a handle construction for pneumatic tools, a cylinder, a back head therefor, a yoke bar across the rear end of said back head, bolts passing through said yoke bar and securing said cylinder, back head and yoke bar rigidly together, a handle having a sleeve portion slidably mounted on 50 said back head, means for guiding and limiting the movement of said handle, a passage in said back head for admitting fluid to said cylinder, and a valve for controlling said passage moving with said handle.

4. In a handle construction for pneumatic tools, a cylinder, a back head, bolts securing said back head to said cylinder, a handle comprising a sleeve portion slidably mounted on the outside of said back head, means 55 for limiting the movement of said handle on said back head, a valve for controlling the flow of fluid to said cylinder, said valve being separate from said handle, and means for moving said valve with said handle.

5. In a handle construction for pneumatic tools, a cylinder, a back head therefor, a yoke bar across the rear end of said back head, bolts passing through said yoke bar and securing said cylinder, back head and 70 yoke bar rigidly together, a handle having a sleeve portion slidably mounted on said back head, means for guiding and limiting the movement of said handle, a passage in said back head for admitting fluid to said cylinder, a valve for controlling said passage, said valve being separate from said handle, and means for moving said valve with said handle.

In testimony whereof, I have hereunto set 75 my hand.

FRANCIS A. JIMERSON.
